UNITED STATES PATENT OFFICE.

GEORGE H. WILKINS, OF BROCKTON, MASSACHUSETTS, ASSIGNOR TO GEO. E. KEITH COMPANY, OF CAMPOLLO, MASSACHUSETTS, A CORPORATION OF MASSACHUSETTS.

SHOE CREASER.

Application filed June 8, 1928. Serial No. 283,894.

This invention relates to an implement of the character shown by Letters Patent of the United States No. 870,265, dated November 5, 1907, for creasing the vamp of a shoe, said 5 implement being adapted for use by a salesman to form creases in the upper part of the vamp while the shoe is being fitted to a customer's foot. The implement comprises a handle and an oblong wire loop, fixed to the 10 handle and including longitudinal parallel side members forming the sides of the loop. Heretofore the wire of which the loop is made has been cylindrical and circular in cross section, so that a crease, formed by reciprocating a side member of the loop and 15 pressing it against the vamp, conforms to the circular cross section of the wire, and is not variable in width by turning or rocking the side member on its longitudinal axis during 20 the creasing operation.

I have found that the vamp may be more advantageously conformed to the foot by widening the crease after it has been initially formed, without increasing its depth, and 25 that such widening can best be effected by rocking the side member on its longitudinal axis while reciprocating it, and exerting pressure on it. I have, therefore, improved the form of each side member of the loop in such 30 manner as to permit the widening of the crease by a rocking movement of a side member of the loop on its longitudinal axis.

Of the accompanying drawings forming a part of this specification,—

35 Figure 1 is a side view of a shoe creaser embodying my improvement.

Figure 2 is an edge view of the same.

Figure 3 is an enlarged section on line 3—3 of Figure 1, looking toward the handle.

40 Figure 4 is a perspective view of a shoe showing creases sunk by the implement in the upper portion of the vamp.

Figure 5 is a fragmentary sectional view, showing the vamp in section on line 5—5 of

45 Figure 4, and the creaser as shown by Figure 3, in position to simultaneously and initially sink two creases in the vamp.

Figure 6 is a view similar to Figure 5, showing the creaser in position to cause the 50 action of only one of its side members.

Figures 7, 8 and 9 are fragmentary sectional views on a larger scale, showing one of

the side members and illustrating the operation of widening a crease without increasing its depth.

55

Figure 7^a shows the creased portion of the vamp shown by Figure 7.

Figure 8^a shows the creased portion of the vamp shown by Figure 8.

Figure 9^a shows the creased portion of the 60 vamp shown by Figure 9.

The same reference characters indicate the same parts in all of the figures.

The general form and construction of the 65 implement excepting the features which characterize my improvement as hereinafter described, may be as disclosed by the above-mentioned patent, the implement comprising an oblong loop of wire, secured at one end to a handle 12, and including longitudinal side 70 members having shanks 13, fixed in the handle, and a neck 14, forming the outer end of the loop.

In describing the side member, I will refer 75 particularly to Figures 5 to 9, showing these members on a larger scale than that shown by Figures 1 and 2. Each side member is designated by 15, and has oppositely inclined flat longitudinal faces 16, and a narrow fillet 17, between said faces. The fillet 80 and the pair of faces 16 converging to it, constitute a longitudinal creasing ridge. The wire may be drawn or otherwise formed, so that it has a plurality of said faces and fillets, and therefore a plurality of creasing ridges, 85 as shown.

The faces and fillet of each ridge are adapted to act conjointly in forming a relatively narrow crease 18 (Figure 7^a) in a vamp 90 19, when the loop member is reciprocated endwise and pressed against the vamp, the bottom of the crease being formed by the fillet, which provides the ridge with a blunt longitudinal apex, so that the bottom of the crease is not objectionably angular.

95 The faces 16 of said ridges are adapted to act alternately in widening the crease without increasing its depth, as indicated by Figures 8 and 9, and Figures 8^a and 9^a. This alternate action is caused by rocking or turning the member 15 on its longitudinal axis. Figure 8 shows the member turned, to cause one of the ridge faces 16 to widen the crease in one direction. Figure 9 shows the mem-

ber turned to cause the other ridge face to widen the crease in the opposite direction.

Figure 5 shows the implement used to initially form two creases simultaneously, creasing ridges of the two side members 15 being pressed against and reciprocated on the vamp.

Figures 6, 7, 8 and 9 show the implement used to widen an initially formed narrow crease, a creasing ridge of only one side member 15 being pressed against and reciprocated on the vamp.

The outer end portions of the members 15 are shown by Figures 1 and 2, as provided with offset protuberances 21, as in the implement shown by the above-mentioned patent, these protuberances having a limited bearing on the vamp and being adapted to set the creases. I prefer to extend the creasing ridges through the said protuberances.

It will now be seen that the implement may be used to simultaneously sink two relatively narrow creases in the vamp, and then to widen said creases by separate operations,

each involving the use of one of the side members 15.

I claim:

1. A shoe-creasing implement comprising an oblong loop of wire, secured at one end to a handle and including a longitudinal side member having flat longitudinal faces oppositely inclined, and a narrow fillet between said faces, the side faces and fillet collectively forming a longitudinal creasing ridge and being adapted to act conjointly in forming a relatively narrow crease, the bottom of which is formed by the fillet, the implement being operable to cause the side faces to act alternately in widening the crease, without increasing the depth thereof.

2. A shoe-creasing implement as specified by claim 1, the side member being provided with a protuberant portion at its outer end, and the creasing ridge being extended through said protuberant portion.

In testimony whereof I have affixed my signature.

GEORGE H. WILKINS.
